(57) **CLAIM**

The ornamental design for a turntable, as shown and described.

DESCRIPTION

FIG. 1 is a top perspective view of a turntable showing our new design;

FIG. 2 is a front elevational view of the turntable of FIG. 1; FIG. 3 is a rear elevational view of the turntable of FIG. 1; FIG. 4 is a side elevational view of one side of the turntable of FIG. 1;

FIG. 5 is a side elevational view of the opposite side of the turntable of FIG. 1; and,

FIG. 6 is a top plan view of the turntable of FIG. 1. The broken line environment is for illustrative purpose and forms no part of the claimed design.

1 Claim, 6 Drawing Sheets(56)
